PRODUCTION OF AROMATIC HYDROCARBONS FROM PETROLEUM

Elton R. Lewis, Roselle Park, and Chester L. Read, Westfield, N. J., assignors, by mesne assignments, to Standard Catalytic Company, a corporation of Delaware

Application June 12, 1941, Serial No. 397,668

9 Claims. (Cl. 260—668)

This invention relates to the production of aromatic hydrocarbons of the type of benzene, toluene and mixed xylenes from petroleum and is more particularly concerned with an improved process by means of which substantially greater yields of these desired aromatic hydrocarbons may be obtained than have heretofore been considered possible.

Virgin fractions obtained from certain crudes are known to contain relatively small quantities of benzene and toluene. Ordinarily, these quantities are so small that attempts to isolate the benzene and toluene in substantially pure form are hardly worthwhile.

Recently a process has been developed according to which virgin petroleum fractions of narrow boiling range which are rich in cyclohexane, methylcyclohexane and dimethylcyclohexanes are subjected to catalytic reforming or catalytic dehydrogenation whereby from 80 to 90% of the cyclohexanes are converted to the corresponding aromatics. In this way, the quantity of benzene, toluene or mixed xylenes may be increased to about 15 to 25% by volume based on the initial petroleum fraction. Following this treatment, the aromatics are recovered in substantially pure form by special types of solvent extraction.

We have now found that substantial quantities of aromatics of the type of benzene, toluene and mixed xylenes and also cyclohexane and derivatives such as methylcyclohexane, dimethylcyclohexanes, and ethylcyclohexane may be obtained by subjecting distillate petroleum fractions to destructive hydrogenation and that upon subsequent catalytic reforming or dehydrogenation of the destructively hydrogenated product the aromatic hydrocarbons remain substantially unchanged whereas the cyclohexanes are largely converted to the corresponding aromatics.

Accordingly, the present invention has for its object the provision of a process by means of which the cyclohexanes normally present in petroleum together with those cyclohexanes which may be formed by destructive hydrogenation are subjected to catalytic reforming and the product of catalytic reforming is subjected to solvent extraction for the recovery of high yields of substantially pure aromatics.

The nature of the process and the manner in which it is carried out will be fully understood from the following description when read with reference to the accompanying drawing which is a semi-diagrammatic view in sectional elevation of one type of apparatus which is suitable for the purpose.

For convenience in description it will be assumed that it is desired to produce substantially pure toluene. It should be understood however that the process is not limited to making toluene but is equally applicable to the production of benzene and mixed xylenes.

Referring to the drawing, numeral 1 designates a supply of a petroleum fraction boiling between the approximate limits of 100 and 500° F. Pump 2 draws oil from tank 1 through line 3 and forces it through line 4 into a fractionating means 5. A fraction comprising hydrocarbons boiling below about 200° F. is removed from the top of the fractionating means through line 6. A fraction comprising hydrocarbons boiling above about 450° F. is removed from the bottom of the fractionating means through line 7. Two side-streams are taken off from the center portions of the fractionating means, one comprising hydrocarbons boiling between about 200 and 250° F. being removed through line 8 and collected in tank 9, and a second comprising hydrocarbons boiling between about 250 and 450° F. being removed through line 10 and collected in a tank 11.

The fraction boiling between 250 and 450° F. is withdrawn from tank 11 through line 12 by means of pump 13 and forced through line 14 into and through a heating means 15. Hydrogen or a gas rich in free hydrogen is supplied to line 14 through line 16 so that a mixture of oil and hydrogen will flow through the heating means 15. The heated mixture of oil and hydrogen flows through line 17 into a reaction zone 18 which is adapted for high pressure destructive hydrogenation and contains a catalytic material 19 which promotes hydrogenation.

Reaction zone 18 is maintained under a pressure in excess of 20 atmospheres preferably at a pressure between 50 and 300 atmospheres or more and at a temperature between 600 and 950° F. The oil is passed through the reaction zone at a rate between 0.5 and 3.0 volumes of liquid oil per volume of catalyst per hour and the quantity of hydrogen which accompanies the oil is between 1000 and 15,000 cubic feet per barrel of oil. The catalyst 19 may be selected from a great variety of different materials which promote hydrogenation. By way of example may be mentioned oxides or sulfides of metals of the VI group of the periodic system either alone or together with oxides of metals of the II and IV groups of the periodic system. Mixtures of molybdenum oxide, chromium oxide and zinc oxide; tungsten sulfide and nickel sulfide or molybdenum disulfide alone are particularly suitable.

Products of the destructive hydrogenation are removed from reaction zone 18 through line 20, passed through a cooling means 21 and then discharged through line 22 into a separating means 23 wherein gaseous and liquid products are separated. Gaseous products of reaction which will consist primarily of hydrogen together with smaller amounts of low molecular weight hydrocarbons such as methane, ethane and propane are removed from separating means 23 through line 24 and may be recycled directly to line 14. A booster compressor 25 may be provided in line 24 to bring the pressure of the recycled gases up to the required pressure in reaction zone 18. It may be desirable also to provide a scrubbing means S in line 24 in order to remove at least a portion of the hydrocarbon constituents from the gases and thereby to increase the concentration of hydrogen in said gases.

Liquid products are removed from separating means 23 through line 26, pass through a pressure release valve 26a and are returned to line 4 and fractionating means 5 by means of pump 27. A fraction boiling between 200 and 250° F. is thus segregated from the liquid products of destructive hydrogenation for further treatment as will presently be described. Another fraction boiling between 250 and 450° F. is also segregated and is returned to the destructive hydrogenation for further treatment.

Returning to tank 9 the fraction boiling between 200 and 250° F., which consists of hydrocarbons separated directly from the initial oil and hydrocarbons separated from the product of the destructive hydrogenation of the 250 to 450° F. fraction of the initial oil, is removed from tank 9 through line 30 by means of pump 31 and forced through line 32 into a heating means 33. Hydrogen or a gas rich in free hydrogen is also introduced into line 32 through line 34. As will be explained below, it is only necessary to supply hydrogen through line 34 when starting up the process about to be carried out in the absence of a supply of hydrogen previously generated in and accumulated from said process.

The mixture of oil and hydrogen heating means 33 flows through line 35 into a reaction zone 36 which contains a catalytic material 37 which promotes catalytic reforming or dehydrogenation.

In reaction zone 36 the fraction boiling between 200 and 250° F. is subjected to catalytic reforming for the principal purpose of converting the methylcyclohexane to toluene. Reaction zone 36 is maintained at a temperature between 850 and 1050° F. and under a pressure between slightly above atmospheric and about 500 pounds per square inch, preferably between 50 and 400 pounds per square inch. The oil is passed through reaction zone 36 at a rate between 0.3 and 3.0 volumes of liquid oil per volume of catalyst per hour, and the quantity of gas containing hydrogen recirculated with the oil is between 1000 and 5000 cubic feet per barrel of oil. This gas should contain between 30 and 90 mol percent of free hydrogen and it will be understood that the larger volumes of gas will be used with the lower concentrations of hydrogen therein and vice versa. The catalytic material 37 in reaction zone 36 may consist of a major amount of aluminum oxide in any of its various forms together with a minor amount of an oxide or sulfide of a metal of the II, IV, V, VI or VIII groups of the periodic system. Suitable catalysts of this type comprise alumina gel, activated alumina, peptized alumina gel and peptized aluminum hydrates impreg-

nated with from 1 to 20% by weight of molybdenum oxide, chromium oxide, vanadium oxide or tungsten oxide.

Products of reaction leave reaction zone 36 through line 38, pass through a cooling means 39 and then discharge through line 40 into a separating means 41 wherein gaseous and liquid products are separated. Gaseous products which consist essentially of hydrogen leave separating means 41 through line 42 and are recycled directly to line 32. A booster compressor 43 is provided in line 42.

Liquid products are removed from separating means 41 through line 44 and introduced into a fractionating means 45 wherein fractions boiling below 200° F. and above 250° F. are separated from the fraction boiling between 200 and 250° F. The lower boiling and higher boiling fractions are removed from fractionating means 45 through lines 46 and 47 respectively. The 200-250° F. fraction is removed from fractionating means 45 through line 48 and introduced into the bottom portion of a tower 49 adapted for the countercurrent flow of two liquids.

Numeral 50 designates a supply tank of a selective solvent which has preferential selective solvent power for aromatic hydrocarbons under conditions at which it has relatively little solvent power for non-aromatic hydrocarbons.

Examples of this type of solvent are liquid sulfur dioxide, phenol, cresol, cresylic acid, beta beta dichloorethyl ether, furfural, aniline and the like. Solvent is withdrawn from tank 50 through line 51 by means of pump 52 and forced through line 53 into the upper portion of the tower 49 wherein it flows downwardly in countercurrent to the upwardly rising hydrocarbon fraction. The preferred solvent for this purpose is liquid sulfur dioxide. It is used in quantities of 60 to 400% of the volume of the hydrocarbon oil to be extracted and especially good results are obtained if the extraction is carried out at a temperature below 0° F., say between -20 and -60° F. or lower.

In tower 49 the liquid sulfur dioxide and oil flow in countercurrent relationship and two phases are formed, a primary raffinate and a primary extract phase. The primary raffinate which will consist chiefly of non-aromatic hydrocarbons and will contain a small amount of liquid sulfur dioxide is removed from tower 49 through line 54. The liquid sulfur dioxide may be removed by distillation and recycled to line 53 which supplies solvent to tower 49.

The primary extract phase which will consist of most of the liquid sulfur dioxide and the aromatics but will also contain small amounts of non-aromatic hydrocarbons is removed from tower 49 through line 55 and introduced into the upper portion of a second tower 56 which is also preferably maintained at a temperature below 0° F. wherein it flows in countercurrent relationship to a non-aromatic hydrocarbon diluent which is supplied to the bottom portion of the tower through line 57.

The non-aromatic hydrocarbon diluent should be a highly paraffinic hydrocarbon oil having a boiling range substantially different from that of the aromatics and the liquid sulfur dioxide. This diluent may have a boiling range either higher or lower than that of the aromatics. Examples of a lower boiling diluent are pentane and iso-pentane. Examples of a higher boiling diluent are a paraffinic heavy naphtha and a light kerosene. For purposes of description, it will be assumed that the non-ar-

matic diluent is a paraffinic hydrocarbon oil boiling between about 350 and 400° F. or higher.

The volume of non-aromatic hydrocarbon diluent with which the primary extract phase is countercurrently washed should be at least sufficient to effect a substantial dilution displacement and may be from about 50 to about 150% or more of the volume of primary extract phase. The volume of non-aromatic diluent should not however be so great as to displace the solvent from the extract phase.

A secondary raffinate phase which will consist chiefly of non-aromatic hydrocarbon diluent, non-aromatic hydrocarbons and some liquid sulfur dioxide is removed from tower 56 through line 58. The liquid sulfur dioxide and non-aromatic hydrocarbon diluent may be separated from the secondary raffinate by distillation. In many cases it is then desirable to recycle the raffinate to the first extraction tower 48.

The secondary extract phase is removed from tower 58 through line 59 and is introduced into a distillation means 60. Liquid sulfur dioxide and non-aromatic hydrocarbon diluent are removed from the distillation means 60 through lines 61 and 62 respectively and may be reused in the extraction process. The remainder of the secondary extract phase is removed from distillation means 60 through line 63 and is introduced into a fractionating means 64 wherein the desired toluene may be separated from the other hydrocarbons with which it may still be associated. The toluene is removed from fractionating means 64 through line 65 and is collected in a tank 66. The fractions boiling below and above toluene are removed from fractionating means 64 through lines 67 and 68 respectively and may be recycled to line 48 for recovery of any toluene which may be present in them. Prior to the final fractionation in fractionating means 64 it may be desirable to subject the aromatic fraction to an acid treatment in order to remove any olefins which may be present. This acid treatment may be carried out in the usual way.

In the operation of the process, the catalytic reforming reaction in reaction zone 36 is carried out for a time and under such conditions that there is either no net consumption of free hydrogen or there is a net production of free hydrogen therefrom. It will be found that the catalyst 37 gradually loses its activity in promoting the desired reforming reactions due to the formation or deposition thereon of carbonaceous contaminants. In most cases after a period of 6 to 12 hours the activity of the catalyst will have fallen to such an extent that there either ceases to be a net production of free hydrogen or the desired reformation of the feed oil is not being obtained. When either of these things happens, the flow of oil is stopped and the catalyst is regenerated by passing hot, inert gases containing regulated small quantities of air or oxygen therethrough in order to burn off the carbonaceous contaminants. Because of the fact that the reforming reaction is conducted under conditions such that there is a net production of free hydrogen, it is not necessary, after once having started up, to supply hydrogen from an extraneous source because the hydrogen initially added and that produced in the reaction may be continuously recycled. It will be understood that any hydrogen that is produced in excess of that required for the reforming reaction may be utilized in the preceding destructive hydrogenation reaction conducted in reaction zone 18. Such

excess hydrogen may be diverted from line 42 through line 78 and forced by means of booster compressor 71 directly to line 24 ahead of the scrubbing means S.

It will be apparent from the foregoing description that the process of the present invention consists of three principal steps, namely (1) destructive hydrogenation, (2) catalytic reforming in the presence of hydrogen and (3) solvent extraction of a type which is capable of making a sharp separation between aromatics and non-aromatics. Numerous modifications may be made in the operation of these three steps. In connection with the solvent extraction step, for example, the description and the drawing have been concerned with the type of solvent extraction in which liquid sulfur dioxide is used at low temperature and the primary extract phase is then subjected to a dilution displacement washing with a non-aromatic hydrocarbon diluent having a boiling range different from that of the hydrocarbons in the primary extract phase. Another type of solvent extraction which is equally suitable for the purposes of the present process is one in which the hydrocarbon fraction is countercurrently extracted in vapor phase with a liquid solvent of substantially higher boiling point characterized by the fact that it depresses the vapor pressure of aromatic hydrocarbons to a much greater extent than it does that of paraffinic or other non-aromatic hydrocarbons. Extraction of the vapors with liquid phenol is an example of this type of extraction.

Although the above description is primarily concerned with the production and recovery of substantially pure toluene it will be understood that with appropriate modifications it is equally capable of producing substantially pure benzene and mixed xylenes. For example, if it is desired to produce benzene a fraction a lower boiling range, say from 120 to 190° F. instead of one boiling between 200 and 250° F. will be selected for the subjection to catalytic reforming. Similarly, if it is desired to produce mixed xylenes a fraction of 240-295° F. boiling range will be selected. To put it another way, when it is desired to produce benzene, the fraction selected for subjection to catalytic reforming will be one which contains chiefly cyclohexane; when it is desired to produce toluene, the fraction selected will be one which contains chiefly methylcyclohexane, and which it is desired to produce mixed xylenes the fraction selected will contain chiefly dimethylcyclohexanes. In each case the fraction of the original oil which is subjected to destructive hydrogenation for the production of additional cyclohexanes of the type desired will be one of higher boiling range than the fraction initially separated from the oil for immediate subjection to catalytic reforming in the presence of hydrogen.

To illustrate how the present process is capable of increasing the yield of toluene from a given petroleum naphtha, a 200 to 250° F. fraction of a virgin naphtha is subjected to catalytic reforming in the presence of hydrogen and the liquid product obtained contains about 20% toluene based on feed. When the higher boiling fractions of this same virgin naphtha are first subjected to destructive hydrogenation and a 200 to 250° F. fraction of the product of destructive hydrogenation is subjected to catalytic reforming in the presence of hydrogen, the liquid product obtained contains about 45% toluene based on feed.

This invention is not limited by any theories of the mechanism of the reactions nor by any details which have been given merely for purposes of illustration but is limited only in and by the following claims in which it is intended to claim all novelty inherent in the invention.

We claim:

1. An improved process for obtaining high yields of substantially pure aromatic hydrocarbons of the type of benzene, toluene and mixed 10 xylenes from a petroleum fraction which comprises separating from said petroleum fraction a fraction containing cyclohexanes which correspond to the aromatic it is desired to obtain, segregating from said petroleum fraction another fraction of higher boiling range than the first fraction separated, subjecting the higher boiling of the two fractions to destructive hydrogenation, segregating from the products of destructive hydrogenation a fraction of approximately the same boiling range as the first fraction separated from the initial petroleum fraction, subjecting the two fractions of the same boiling range, one obtained directly from the initial petroleum fraction and the other obtained from the products of destructive hydrogenation, to catalytic reforming, separating from the products of catalytic reforming a fraction of narrow boiling range which contains the desired aromatic, and recovering the desired aromatic from this narrow boiling fraction by solvent extraction.

2. Process according to claim 1 in which the narrow boiling fraction separated from the products of catalytic reforming is first extracted with liquid sulfur dioxide at a temperature below 0° F. whereby a primary raffinate and a primary extract phase are obtained, countercurrently washing the primary extract phase with a non-aromatic hydrocarbon diluent having a boiling range substantially different from the hydrocarbons and liquid sulfur dioxide present in the primary extract phase whereby a secondary raffinate and a secondary extract phase are obtained, removing the liquid sulfur dioxide from the secondary extract phase and recovering substantially pure aromatic of the type desired from the solvent-free secondary extract phase by fractionation.

3. Process according to claim 1 in which the narrow boiling fraction separated from the products of catalytic reforming is extracted in vapor phase with a liquid solvent of substantially higher boiling point characterized by the fact that it depresses the vapor pressure of aromatic hydrocarbons to a greater extent than it does that of non-aromatic hydrocarbons.

4. Process according to claim 1 in which the catalytic reforming is conducted in the presence of hydrogen for a time and under such conditions that there is an overall net production of free hydrogen.

5. An improved process for obtaining high yields of substantially pure toluene from a petro-

leum fraction which comprises segregating from said petroleum fraction two fractions of narrow boiling range, one boiling between about 200 and 250° F. and the other boiling between about 250 and 450° F., subjecting the fraction boiling between 250 and 450° F. to destructive hydrogenation, segregating from the products of destructive hydrogenation a fraction boiling between 200 and 250° F., combining the two fractions boiling between 200 and 250° F., subjecting these to catalytic reforming, segregating from the products of catalytic reforming a fraction boiling between 200 and 250° F., subjecting this last-mentioned fraction to extraction with liquid sulfur dioxide, and recovering substantially pure toluene from the extract phase so obtained.

6. Process according to claim 5 in which the fractions of the products of destructive hydrogenation boiling between 250 and 450° F. are recycled to the destructive hydrogenation.

7. Process according to claim 5 in which the fraction boiling between 200 and 250° F. which is separated from the products of catalytic reforming is extracted with liquid sulfur dioxide at a temperature below 0° F. whereby a primary raffinate and a primary extract phase are obtained, the primary extract phase is countercurrently washed with a non-aromatic hydrocarbon diluent of a boiling range different from that of the hydrocarbons and the liquid sulfur dioxide in the primary extract phase whereby a secondary raffinate and a secondary extract phase are obtained, the liquid sulfur dioxide is removed from the secondary extract phase and substantially pure toluene is recovered from the solvent-free secondary extract phase by fractionation.

8. Process according to claim 5 in which the catalytic reforming is conducted in the presence of hydrogen for a time and under such conditions that there is an overall net production of free hydrogen.

9. An improved process for obtaining high yields of substantially pure toluene from a petroleum fraction which comprises segregating from said petroleum fraction two fractions of narrow boiling range, one boiling between about 200 and 250° F. and the other boiling between about 250 and 450° F., subjecting the fraction boiling between 250 and 450° F. to destructive hydrogenation, segregating from the products of destructive hydrogenation a fraction boiling between 200 and 250° F., combining the two fractions boiling between 200 and 250° F., subjecting these to catalytic reforming, segregating from the products of catalytic reforming a fraction boiling between 200 and 250° F., subjecting this last-mentioned fraction in vapor phase to extraction with liquid phenol, and recovering substantially pure toluene from the extract phase so obtained.
